By *John J. Devereux*
Attorney.

UNITED STATES PATENT OFFICE.

WILLIAM H. SLATTERY, OF NEW YORK, N. Y., ASSIGNOR TO THE BELBER TRUNK & BAG COMPANY, OF PHILADELPHIA, PENNSYLVANIA, A CORPORATION OF PENNSYLVANIA.

FASTENER AND TAG HOLDER.

1,409,252.

Specification of Letters Patent. Patented Mar. 14, 1922.

Application filed November 3, 1919. Serial No. 335,275.

To all whom it may concern:

Be it known that I, WM. H. SLATTERY, a citizen of the United States, residing in the city of New York, county of New York, 5 and State of New York, have invented an Improved Fastener and Tag Holder, of which the following is a specification.

My invention is an improved article of manufacture designed particularly for use 10 in connection with luggage to provide a tag holder in which an indicia member can be readily inserted and withdrawn and by which the name inscribed on such indicia member will be prominently displayed. In its 15 preferred form, it comprises a flat body of laminated material having a narrow medium section by which it is secured to a part of the luggage. On end of the body contains a fenestration through which is displayed a 20 tag inserted between the laminæ of material through a slot adjacent to but on the opposite side of the body from the display aperture. The other end of the body is preferably provided with an element of a 25 snap fastener adapted for coaction with a complementary snap fastener member on the luggage, the fastened end of the body acting as a strut to hold the fenestrated end flat against the member to which it is attached. 30 In the accompanying drawings, Fig. 1 is a front elevation of a device embodying my invention; Fig. 2 is a rear view thereof; Fig. 3 is an elevation of the tag; and Fig. 4 is a fragmentary part sectional view of 35 a traveling bag lid having my invention applied thereto.

As shown in the drawings, my invention 40 comprises a flat body of sheet material consisting of a face 1 and a back 1' secured together by marginal stitching 1^a, the material used being preferably leather or leather substitute possessing a certain amount of stiffness. An aperture 2 is cut in the front 1 and a slot 3 is cut in the back 1' 45 adjacent to this aperture for the insertion of an indicia member or tag 4 between the laminæ of the body. The tag is provided with a tab 4' projecting through the slot 3 and is disposed behind the fenestration 2 through which is displayed the name or 50 legend on the tag.

A fastener 6 is attached to the end of the body opposite the fenestration 2.

In the usual application of my invention, the narrow neck between the ends of the 55 body is secured by stitching 5 to a luggage member B against which the fenestrated end of the body is held by the engagement of the fastener 6 with a complementary stud or button 7 on the partition A normally movable relatively to the member B but held in place by the engagement of the fastener members. The tab 4' projecting through the slot 3 permits the ready substitution of 60 one tag for another, as, for instance, a tag 65 bearing the name of a purchaser in lieu of a tag bearing the name of the maker of the article.

Having described my invention, I claim:

1. An article of the character described 70 comprising a flat body of sheet material having enlarged ends and a narrow neck by which said article may be hingedly fixed to a container, one of said enlarged ends having a fenestration in the face thereof and 75 a slot in the back thereof adjacent to said fenestration, and a tag disposed within said body behind said fenestration.

2. An article of the character described 80 comprising a body composed of laminæ of sheet material secured together along their entire peripheries, and a tag disposed between said laminæ, one of said lamina containing an aperture through which said tag is displayed and the other lamina containing an opening for the insertion of said tag.

3. An article of the character described 90 comprising a flat body of sheet material having a fenestration in the face thereof adjacent to one end, and a tag within said body behind said fenestration, in combination with a member to which said body is secured approximately midway between its ends.

4. An article of the character described 95 comprising a flat body of sheet material having a median neck of less width than the ends, one of said ends containing a fenestration and the other of said ends having a 100 fastener attached thereto for holding the fenestrated part of said body in proper display position, and a tag disposed behind said fenestration.

5. An article of the character described 105 comprising a body containing a fenestration

and a slot adjacent thereto, a tag disposed within said body behind said fenestration, and a fastener attached to said body, in combination with a plurality of members one of which is movable relatively to the other, said body being secured between said fenestration and fastener to one of said

members, and the other of said members having attached thereto a fastener adapted to coact with said fastener first named.

In testimony whereof, I have hereunto set my name this 10th day of October, 1919.

W. H. SLATTERY.
